UNITED STATES PATENT OFFICE.

KYLE M. ANDERSON, OF ECHO, OREGON.

WATER-MOTOR.

1,342,613.

Specification of Letters Patent.

Patented June 8, 1920.

Application filed July 14, 1919. Serial No. 310,570.

To all whom it may concern:

Be it known that I, KYLE M. ANDERSON, a citizen of the United States, resident at Echo, in the county of Umatilla and State 5 of Oregon, have invented certain new and useful Improvements in Water-Motors, of which the following is a specification.

The present invention relates to improvements in water motors, designed particularly for use in slow moving or flowing streams, and embodying instrumentalities for transforming an oscillating movement of a lever mechanism actuated by weight of water, into a continuous rotary motion, and 10 provides an inexpensive source of power for running an irrigating pump, etc., where only a slow motion of the mechanism is required.

The invention involves the utilization of a 20 hollow buoyant tank adapted to be filled with water, which when loaded, by its own weight imparts a working stroke to an oscillatable lever, and which tank is automatically emptied at the end of its working 25 stroke, so that by its buoyancy the tank is returned to position to be again filled with water for a successive working stroke.

In the accompanying drawings one complete example of the physical embodiment of 30 the invention is illustrated, the parts being combined and arranged according to the best mode so far devised for the practical application of the principles of the invention.

35 Figure 1 is a top plan view of the apparatus involving the invention.

Fig. 2 is a sectional view of an inclosure 40 for retaining water, showing the apparatus in side elevation partly broken away.

Fig. 3 is an enlarged view, partly in section, of the outlet valve of the buoyant tank, and connections.

In the preferred embodiment of the invention as illustrated in the drawings I have 45 utilized a barrel, 1, of usual construction as the buoyant tank, it being understood that this vessel is shown as a convenient and comparatively inexpensive receptacle or tank, for the purpose. The tank is secured near the 50 end of an oscillatable lever in the nature of a long tube or pipe 2, which has at 3 an opening into the tank at its upper portion, and at or near its opposite end the lever is provided with a pivot bearing 4 so that it 55 may oscillate in the supporting bracket 5 provided therefor.

The long arm of the lever is designed to move between a pair of parallel, curved, upright guides 6, preferably made of angle iron strips and secured rigidly to the retaining wall 7 of the inclosure in which the water for the buoyant tank is contained, the water line being indicated at W. L. in Fig. 2. The buoyant tank is adapted to swing the lever on its pivot, and the upward movement of 60 the tank is governed by mechanism actuated by contact with the stop pin 8 between the two angle irons of the lever guide, and preferably this pin is so located that the tank does not rise to the extreme position 65 on the surface, permitted by its buoyancy, in order that the water may enter the tank to fill it. In Fig. 2 the tank is shown in dotted lines, as still submerged, although at the extreme of its uplifted position, and 70 also in this figure the tank is shown in full lines at its lowermost position where it is held by the locking latch 9 engaging the keeper 10, which latter is a bracket fixed on the wall 7 of the water inclosure. 75

The tank is adapted to swing with the oscillatable lever between the two extreme positions indicated in Fig. 2, its idle stroke being the down stroke that is caused by the filling of the tank through an inlet member 80 11 fastened by its flange 12 about an opening through the under wall of the tank. The member 11 is normally held closed by the valve 13 in its seat 14 in the head of the member 11 and a spring 15 holds the valve 85 to its seat as in Fig. 3 where the spring is shown interposed between the valve and a yoke 16 therefor.

The valve is opened, when the empty tank rises to its proper height by the action of a 90 trip lever 17 pivoted at 18 on a rigid arm or support 19 on the tank and connected by link 20 and push pin 21 with the bell crank lever 22 pivoted at 23 in the member 11. The link pin 21 passes through and is supported in an opening in the wall of the member 11, and the bell crank lever against which the pin pushes is pivoted at 24 to the stem 25 of the valve. The action of this 100 valve opening mechanism will be evident 105 when the rising tank causes the trip lever to engage and swing around and hold the pin 8 in the guides 6, to push the valve open against the tension of the spring 15 as understood.

The valve is held open so that water may 110 enter the tank, forcing the air therefrom

through the lever pipe 2 which is open to the atmosphere at the end 2', and the filling tank, by the weight of the water and its own weight, sinks to the lower position, 5 making the idle stroke of the lever, and at the end of this stroke, the valve is automatically opened as will be described, while the tank is held or retained by the latch 9.

In the bottom of the water receptacle or 10 inclosed area, a concrete base or structure 26 is provided through which a spillway 27 passes, opening outside of the wall 7, and at its inner end fashioned with a valve seat 28 for the outwardly opening valve 29 which 15 is held normally closed by the spring 30 beneath it, and the stem of the valve, as 31, when the valve is closed, projects up and through the valve seat 28.

The valve 29 and its stem 31 are located 20 directly in the path of movement of the stem 25 of the valve 13, and the spillway is provided with an annular shoulder 32 forming a seat directly in the path of the member 11 carried by the tank. Thus, as shown in 25 Fig. 2 the tank has descended, of its own weight, to its lowermost position and is locked by the latch 9, the member 11 is engaging the shoulder or seat 32 of the spillway closing the spillway against communication 30 with the interior of the water receptacle, and the two valve stems 25 and 31 are engaged, lifting their valves or removing their valves from their seats. Under these 35 conditions water is free to pass from the tank through the member 11, two valve seats, and the spillway out through the open end of the spillway, to render the tank once more buoyant after the water has flowed therefrom.

40 The emptied tank, however, remains held or retained in lowered position until the latch 9 is released, and this release is accomplished through the connecting rod 36, arm 37 and eccentric 38, the latter on a shaft 45 39 having a sprocket wheel 40 connected by sprocket chain 41 to a similar sprocket 42 on the shaft 43. The shaft 43 is the main shaft of the actuating mechanism and is driven from the short arm of the lever pipe 50 through the pivoted link 44 on the lever and the pivoted arm 45 on the shaft 43. The arm 45 carries a pawl or dog 46 which engages the ratchet wheel 47 on the main shaft 43, and it will readily be seen that the movement of the short arm of the pipe lever will turn the ratchet wheel in one direction, step by step with the rising and falling of the tank, the quick upward swing of the long

arm of the lever being the working stroke which turns the ratchet wheel through its 60 ratchet or pawl connection. The throw of the pawl may be adapted or altered by moving the pivotal connection 48 to selected holes 49 in the arm 45, and the action of this ratchet mechanism results in turning 65 the main shaft in one direction to operate a pump or other device as described, the momentum being stabilized by a fly wheel as usual.

Claims:

1. The combination with the pivoted lever, buoyant tank and spring pressed valve closing an opening in the tank, and valve opening mechanism carried by the tank, means coacting with said mechanism to submerge the tank, an automatic latch device for retaining the tank in submerged position and means for releasing said latch when the tank is emptied, a spillway, and an inwardly opening valve in the spillway in the path of 80 said spring pressed valve for opening the latter while the tank is submerged to restore the buoyancy of the tank and cause a working stroke of the lever.

2. The combination with the pivoted lever 85 and a buoyant tank thereon having a normally closed opening and adapted for submersion, means for admitting water to the tank for its submersion, automatic means for emptying the tank, and means for retaining the tank while it is being emptied, for the purpose described.

3. The combination with the pivoted lever and its normally closed buoyant tank, of means for admitting water to the tank to 95 submerge the tank, means for emptying the submerged tank to restore its buoyancy, means for retaining the tank while being emptied, and means for guiding said lever in its movements.

4. The combination with the pivoted lever, buoyant tank and spring pressed valve closing an opening in the tank, and valve opening mechanism carried by the tank, of guides for the lever and a stop thereon to co-act 105 with said mechanism to submerge the tank, an automatic latch device for retaining the tank in submerged position and means for releasing said latch when the tank is emptied, and means for opening the spring 110 pressed valve while the tank is submerged to restore the buoyancy of the tank and cause a working stroke of the lever.

In testimony whereof I affix my signature.

KYLE M. ANDERSON.
